US00D617288S

(12) **United States Design Patent**
Yang

(10) **Patent No.:** **US D617,288 S**
(45) **Date of Patent:** **** Jun. 8, 2010**

(54) **DEFINITE PURPOSE (DP) CONTACTOR FOR AIR-CONDITIONING SYSTEMS**

(75) Inventor: **Qinghua Yang**, Suzhou (CN)

(73) Assignee: **Siemens Aktiengesellschaft**, Munich (DE)

(**) Term: **14 Years**

(21) Appl. No.: **29/237,843**

(22) Filed: **Sep. 8, 2005**

(30) **Foreign Application Priority Data**

Mar. 9, 2005 (CN) 2005 3 0034748

(51) **LOC (9) Cl.** **23-01**

(52) **U.S. Cl.** **D13/159**

(58) **Field of Classification Search** D23/341; D13/146-147, 158-159, 160; 200/280, 303, 200/293, 294, 297; 335/131-133, 202, 196, 335/262, 251

(57) **CLAIM**

The ornamental design for a definite purpose (DP) contactor for air-conditioning systems, as shown.

DESCRIPTION

FIG. 1 is a front elevational view of a definite purpose (DP) contactor for air-conditioning systems showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a perspective view thereof.
